MATCH-CARD

No. 837,283.

Specification of Letters Patent.

Patented Nov. 27, 1906.

Application filed March 13, 1906. Serial No. 305,803.

To all whom it may concern:

Be it known that I, MARTINUS LARSEN, a citizen of the United States, residing at 183 Harrison street, Brooklyn, New York, have 5 invented certain new and useful Improvements in Match-Cards, of which the following is a clear, full, and exact description.

This invention relates to improved match-cards, such as the pliable paper sheets of 10 matches now well known.

The object of the invention is to so form the card that the match-heads may be more uniformly and certainly detached than heretofore, that they may occupy the minimum 15 of space, particularly as to thickness, that they shall present a pleasing appearance to the eye, that they be of a form to enable ready and cheap manufacture, and that the match-heads shall be so located one with relation to another that liability to rub surfaces shall be prevented as much as possible, all without producing waste of material or 20 increasing the intricacy of manufacture.

In carrying out my invention I provide a 25 uniting-strip from which the splints project with their butt-ends preferably more frangible than the rest of the splints, and I prefer that this uniting-strip be secured to or form part of a retaining element which I prefer to 30 provide as a rectangular frame, from opposite sides of which the splints project. I prefer that the arrangement of the splints on a single sheet be such that they constitute two series, one series being secured to one strip 35 of the frame with intervening spaces at least of the width of a splint and the other series being likewise formed, but secured to the opposite strip, with the splints so located that they will occupy a position in said spaces.

40 This can readily be secured by stamping the entire frame and two series of splints from one integral sheet, but not necessarily so. When two such sheets are to be secured together as a folder, I so locate the free ends or 45 igniting-heads of one strip that they will come opposite the butts of the splints of the other strip when said folder has been folded like a book. I also prefer that recesses shall be formed in the strips or in the strips and 50 part of the butt-ends to form reception-pockets for the heads of an opposing series of matches. By forming these recesses I am enabled to assemble two sheets with a thickness less than the combined thickness of two 55 match-heads, as is obviously desirable. Preferably I so form the frame and the direction

of projection of the splints that a mere compression of the retaining-strips toward each other will cause the splints to assume a position projecting without the plane of the 60 sheet, with each head preferably free from contact with its neighbor, and where two series such as herein described are present, with the splints of one series crossing the splints of the other series like a letter X, it will be obvious 65 that this arrangement provides a simple means for either machine or hand dipping of the tips.

My invention will be pointed out in the 70 claims.

In the accompanying drawings, Figure 1 is a plan view of a single sheet of match-splints according to my invention, and it shows one splint as raised preparatory to being detached. Fig. 2 shows a plan view of a double 75 sheet or folder with cover attached. Fig. 3 is a perspective view of Fig. 1, showing how compression of the strips will extend the match-splints from the plane of the sheet. Fig. 4 is a perspective view of the folder of 80 Fig. 2. Fig. 5 is a view similar to Fig. 1 of a modification, and Fig. 6 is a view of a part of a strip from which the device of Fig. 5 is made up.

My preferred form of match-sheet is shown 85 in Figs. 1 to 4, inclusive, in which the uniting-strips 1 and 2 form opposite sides of a rectangular frame having ends 3 and 4. The splints themselves are shown as arranged in two series, splints x belonging to one series 90 and joined to strip 1, while splints y of the other series are joined to strip 2. The strips and splints near their butt-ends are so cut out as to leave a recess 5 adjacent to the butt-ends. The formation of these recesses 95 partly out of the splints themselves produces a reduced cross-section on the splint at 6 near its end and greatly facilitates the removal by breaking at the proper place. The recesses have a second function and advantage, as will be seen from the following. The splints y of one series are so placed that they nicely fit between the adjacent splints of series x. Their heads consequently will lie in the recesses 5. Where all the splints and retaining-strips or frame are made of one piece, 100 as shown in these figures, it will be obvious that the splints all occupy the same plane with their edges parallel and with the head of any match x of one series in a recess 5 and lying between the butt-ends of two adjacent 105 splints y of the opposite series. As shown in

Fig. 3, the mere compression of the strips 1 and 2 toward each other will bow the end strips 3 and 4 and cause the splints *x* and *y* to cross each other like a letter **X**, each free end of the splints being well separated from its neighbor, as the splints project tangentially to the curved end strips. It is in this position that I prefer to dip the ends.

In Fig. 2 I have shown two sheets joined on a mid-line and secured by staples 7 to a cover 8, having a flap 9 to fit, as shown in Fig. 4, into a slit 11 when folded. An igniting-strip 13 may be attached to or formed on the cover, as illustrated, preferably near the fold where greatest stability is obtained. It will be noticed in Fig. 2 that the left-hand sheet has each splint *y* arranged with its butt-end near the fold and the head of splints *x* next the fold, while on the right-hand sheet the splints *y* have their heads next the fold and splints *x* their butts next the fold. By this arrangement the heads of one series of one strip will come opposite the butt-ends of the other strip, and thus take up less room, at the same time preventing rubbing off of one igniting-head against another.

As shown in the modification of Figs. 5 and 6, the uniting-strip 10 is formed of a continuous strip having splints projecting therefrom with intervening spaces instead of being formed of an integral sheet. I secure two such strips to a retaining element, in this case a sheet of cardboard or the like 14, with the splints in the same relative position shown in the figures before described. They are shown as attached by staples 15 to retaining element 14.

By the term "retaining element" as set forth in my claims I intend to include and define any element from which the match-strips may project and be held in position, which is shown as a rectangular structure in Figs. 1, 2, and 3 of my drawings and as a sheet of paper 14 secured to the bands 10 of Figs. 5 and 6, in which structure the band 10 itself comprises a part of the retaining element.

I claim as my invention—

1. A match-card of suitable flexible material whose exterior edge is intact, and with the interior body slit into splints, each pair of slits ending in a circular cut whereby each alternate splint is free at one enlarged end forming the head, the other end being correspondingly diminished in size.

2. A match-card comprising a retaining element, splints of considerable width and little thickness projecting therefrom, the splints lying side by side with a space between for the greater part of their length and at a greater distance from each other at their joinder with the retaining element.

3. A match-card comprising a retaining element, match-splints thereon having their edges parallel, and secured at their butt to

the retaining element, the butt of one match lying between the heads of adjacent matches.

4. A match-card comprising a retaining element, match-splints thereon having their edges parallel, and secured at their butt to the retaining element, the butt of one match lying between the heads of adjacent matches, alternate match-splints being at a greater distance apart at their butt than throughout their length, whereby a recess is formed to receive the match-head lying between said butt-ends.

5. A match-card comprising a retaining element composed of an integral rectangular structure, at least a series of separated match-splints joined at their butt-ends to one side of the structure, and a second series of match-splints joined in like manner to the opposite side so that the splints of the second series will lie between those of the first series.

6. A match-card comprising a retaining element composed of an integral rectangular structure, a series of separated match-splints joined at their butt-ends to one side of the structure and a second series of match-splints joined in like manner to the opposite side so that the splints of the second series will lie between those of the first series, said structure having recesses to receive the match-heads.

7. A match-card comprising a retaining element composed of an integral rectangular structure, a series of separated match-splints joined at their butt-ends to one side of the structure and a second series of match-splints joined in like manner to the opposite side so that the splints of the second series will lie between those of the first series, said splints being formed of reduced width near their butt-ends to produce a frangible point for the splints, the heads of the opposite series of splints lying in the recesses formed by the sides of the reduced portions.

8. A match-card comprising a retaining element, match-splints thereon having their edges parallel, and secured at their butt to the retaining element, the butt of one match lying between the heads of adjacent matches, in combination with a second retaining element, with match-splints thereon, and joined to said first element to form a folder.

9. A match-card comprising a retaining element, match-splints thereon having their edges parallel, and secured at their butt to the retaining element, the butt of one match lying between the heads of adjacent matches, in combination with a second retaining element, with match-splints thereon, and joined to said first element to form a folder, said line of joinder being at right angles to the length of the splints.

10. A match-card comprising two opposite retaining elements, a hinge joining them, splints carried by each element, the combined space occupied by two heads of opposite

site elements when in folded position being less than their combined thicknesses.

11. A retaining element for match-splints comprising a rectangular structure having 5 opposite uniting - strips and match - splints joined thereto at their butt-ends, said structure being compressible whereby on compressing the strips toward each other the matches will be caused to project from the 10 surface of frame.

12. A match-card comprising a retaining element, match-splints thereon having their 15 edges parallel, and secured at their butt to the retaining element, the butt of one match lying between the heads of adjacent matches, in combination with a second retaining element, with match - splints thereon, and joined to said first element to form a folder, with the heads on one sheet opposite the 20 butts on the other when folded together bookwise.

13. A match-card comprising two opposite retaining elements, a hinge joining said

elements, splints carried by each element, heads on the splints, the combined space occupied by two heads on opposite elements when in folded position being less than their combined thicknesses, said heads being partially located within the plane of the retaining element which carries them. 25

14. A match-card comprising two opposite retaining elements, a hinge joining said elements, splints carried by each element, heads on the splints, the combined space occupied by two heads on opposite elements 30 when in folded position being less than their combined thicknesses, said heads being partially located within the plane of the retaining element which carries them, the heads of opposite elements being free from contact. 40

Signed at New York city this 7th day of March, 1906.
